UNITED STATES PATENT OFFICE.

PATRICK H. DONOVAN, OF CHICAGO, AND LAURENCE J. BERKELEY, OF EVANSTON, ILLINOIS, ASSIGNORS TO THE P & M COMPANY, OF CHICAGO, ILLINOIS, A CORPORATION OF ILLINOIS.

RAIL ANCHOR.

Application filed October 22, 1923, Serial No. 670,020. Renewed September 27, 1924.

To all whom it may concern:

Be it known that we, PATRICK H. DONOVAN and LAURENCE J. BERKELEY, citizens of the United States, residing, respectively, at

5 Chicago, in the county of Cook and State of Illinois, and Evanston, Illinois, have invented certain new and useful Improvements in Rail Anchors, of which the following is a specification.

10 Our invention relates to rail anchors and particularly to the general type of anchors in which a rigid member and a spring bar cooperate to embrace the base of the rail and are maintained in their operative position on the rail by spring pressure produced by distorting the spring bar during its application.

One of the objects of the invention is to provide an improved anchor of the above 20 general character in which the spring bar is so positioned between the rail base and a part of the rigid member as to effect a firm positive grip on the rail when the rail is subjected to a force tending to move it longitudinally.

Another object is to provide an anchor of the above general type in which the gripping action of the device is so effected as to permit a relatively light spring to be used and in 30 which the spring is so formed as to increase its flexibility and thereby facilitate its application to the rail and permit a greater range of distortion than other types of spring bars now in general use without sacrificing the 35 resiliency required to maintain the anchor as a whole in its proper operative position.

Then invention has for a further object such other novel arrangements constructions and combinations of parts hereinafter described and claimed for carrying out the above stated objects and such other objects as will appear in the following description.

The invention is illustrated in certain preferred embodiments in the accompanying drawings, wherein—

45 Fig. 1 is a front view in elevation of a two-piece rail anchor device constructed in accordance with this invention.

Fig. 2 is a side view in elevation of the 50 structure shown in Fig. 1.

Figs. 3 and 4 are side and top views respectively of the spring bar member used in connection with the form of anchor shown in Figs. 1 and 2.

Fig. 5 is a view similar to Fig. 1 illustrating a modified form of spring bar.

Fig. 6 is a view in perspective of another modified form of anchor, and

Fig. 7 is a side view of the modification illustrated in Fig. 6.

Like characters of reference indicate like parts in the several figures of the drawings.

Referring first to Figs. 1 to 4 inclusive of the drawings: 10 designates a rigid member or shoe adapted to engage one edge of the rail base and 11 a spring bar formed to maintain the rigid member in operative position and adapted to grip opposite edges of the rail base 12. The rigid member is made, preferably of cast metal and is provided with upper and lower jaws 13 and 14, respectively, which are joined together by a vertical web 15 and fit over one edge of the rail base. A depending flange 16 is formed at one end of the jaw portion 10 to provide 75 a suitable abutment for bearing against one of the vertical faces of a cross tie 17. A depending flange 18 is formed at the other end of the jaw portion and is provided with a projection or arm 19 which extends longitudinally of the rail below the base 12, which arm is formed with a notch 20 to provide a suitable seat for the spring bar 11. The depending flanges 16 and 18 are reenforced by 80 a connecting web 21.

The spring bar 11 is formed at one end with a jaw portion 22 having an angularly disposed lip 23 bent in a direction away from the cross tie and adapted to bear upon the upper surface of the rail base on the 90 side of the rail opposite to that engaged by the rigid member 10. The body of the spring tapers in a direction towards the rigid member as shown by the reference numeral 24, to increase its flexibility, and terminates in an enlarged dovetail portion 25, which is disposed in an angular position between the lower edge of the rail base and the projection 19 of the rigid member 10 so as to function as a toggle when the 100 rail is subjected to creeping pressure. The edges 26 and 27 of the enlarged portion 25 diverge from each other toward the end of the bar so that the edge engaging the lower edge of the rail base projects above the said lower edge of the base and thereby causes the bar 11 to function as a spring yoke which embraces the opposite edges of

85

95

100

105

the rail base. The lower edge of said dovetailed portion projects below the seat portion of the notch 20 and thereby prevents the spring from shifting in the direction of its length transversely of the rail and also prevents lateral movement of the rigid member with relation to the rail. The spring member is normally flat and is of greater width than the distance between the projection 19 and the under surface of the rail base at the point engaging these members, whereby it is necessary to cant the spring body to permit the dovetail portion to be positioned between the projection 19 and the rail base. The torsioning of the spring increases the grip of the jaw portion 22 on the rail and exerts sufficient resilient pressure against the rigid member to resist any tendency that the vibration of the rail or the movement of the device through the ballast of the roadbed may have to loosen the initial hold of the anchor on the rail.

In operation, the rigid member is fitted over one edge of the rail in a position to bear against a cross tie. The jaw portion of the spring bar may then be hooked over the other edge of the rail and the body of the spring twisted sufficiently to permit the dovetail portion 25 of the spring to be positioned between the rail base and the projection 19 of the rigid member or shoe 10. The body portion of the spring intervening between its dovetail and jaw portions being reduced in cross sectional area increases the flexibility of the spring and also, due to its small area of contact with the under surface of the rail, prevents any rough spots that may be on the under surface of the rail from interfering with the proper gripping engagement between the dovetail portions and the rail base. The spring bar normally stands at right angles to the length of the rail but may be readily shifted to a position diagonally across the rail if such position is required to accommodate rails having base flanges of less width than that shown in the drawings.

In Fig. 5 a modified construction is illustrated in which the upper edge 26^a of the enlargement 25^a of the spring 11^a is formed parallel to the lower surface of the rail base so as to grip a larger area of the under surface of the rail base than the form shown in Figs. 1 to 4 inclusive. In other respects this modification may be and preferably is the same as that shown in Figs. 1 to 4 inclusive of the drawings.

In Figs. 6 and 7 another modified construction is illustrated in which the rigid member or shoe consists of two flange members each of which is formed with a recess 30 which fits over and engages with the upper and lower surfaces of the rail base. The flanges 28 and 29 are secured together near their upper ends by means of an an-

gular jaw portion 31 which bears against the upper surface of the rail base. The vertical portion 32 of this jaw portion however stops short of the lower edge of the rail base so that it will not interfere with the proper grip of the spring on the lower edge of the rail. The lower portions of the flanges 28 and 29 are secured together by means of an integral arm 33 which in this modification functions in the same manner as the arm or stud 19 in the Figs. 1 and 2.

The spring bar member as shown in this modification may be the same as either of the forms shown in Figs. 1 or 5. However, for the purpose of convenience the spring bar shown in Figs. 1 to 4 inclusive is used in connection with this modification as a specific illustration and has been given corresponding reference numerals with the exponent "b".

In operation the jaw end 22^b of the spring bar 11^b is first hooked over one edge of the rail base with the body of the bar extending transversely of the rail. Suitable applying tongs (not shown) may then be extended through the opening 34 of the rigid member a distance sufficient to grasp the dovetail portion 25^b of the spring bar. The spring bar may then be torsioned sufficiently to permit the dovetail portion 25^b to pass through the opening 34 of the rigid member, the spring may then be released, whereupon the inclined upper and lower edges 26^b, 27^b will be forced into engagement with the lower corner of the rail base and with the arm 33 and held in such engagement by means of the torsion to which the spring has been subjected. When the rail tends to move in the direction toward the tie the creeping movement tends to move the portion 25^b of the spring member toward a vertical position whereby the portion 25^b becomes tightly cramped between the rail base and the arm 33.

While the invention herein has been shown in certain specific embodiments in which the flexibility of the spring is increased by reducing the width of the spring, it will be obvious that the flexibility of the spring may be increased in other ways than illustrated therein and that the various other features of the invention might be accomplished by modified structure. It should therefore be understood that this invention contemplates all such modifications in structure as come within the scope of the appended claims.

We claim:

1. A rail anchor comprising a jaw member for engaging one edge of a rail base and a toggle member interposed between the rail and the jaw member to effect a toggle grip on the rail during the presence of creeping pressure.

2. A rail anchor comprising a jaw mem-

ber for engaging one edge of a rail base and a toggle member provided with means for engaging the other edge of the rail and interposed between the rail and the jaw member to effect a toggle grip on the rail during the presence of creeping pressure.

3. A rail anchor comprising a jaw member for engaging one edge of a rail base and a bar provided at one end with a jaw portion for engaging the other edge of said base and at the other end with a toggle portion adapted to be interposed between the rail and said jaw member, whereby toggle pressure is exerted against the rail during the presence of creeping pressure on the rail.

4. A rail anchor comprising a jaw member for engaging one edge of a rail base and a bar provided at one end with a jaw portion for engaging the other edge of said base and at the other end with a toggle portion adapted to be interposed between the lower edge of the rail base and a portion on said jaw member, whereby toggle pressure is exerted against the rail during the presence of creeping pressure.

5. A rail anchor comprising a rigid member formed to engage one edge of the rail base and to engage with a cross tie and a bar provided at one end with a jaw portion for engaging the other edge of said base and at the other end with a toggle portion adapted to be interposed between the lower edge of the rail base and a portion on said rigid member, whereby toggle pressure is exerted against the rail during the presence of creeping pressure.

6. A rail anchor comprising a rigid member formed with a jaw portion for engaging one edge of the rail base and a spring bar formed at one end with a jaw for engaging the other edge of said base and with a toggle portion adapted to be positioned between a portion on the rigid member and the under surface of the rail base; the body portion of the spring bar intervening between its jaw and said toggle portion being adapted to be torsioned during the application of the spring to its operative position to effect a spring grip of its jaw on the rail.

7. A rail anchor comprising a rigid member for engaging one edge of a rail base and formed with a projection extending longitudinally of the rail and with a portion for abutting against a cross tie, and a spring bar adapted to engage opposite edges of the rail base; one end of said spring bar being supported in an angular position between said projection and the rail base to effect a toggle grip on the rail during the presence of a creeping pressure.

8. A rail anchor comprising a rigid member for engaging one edge of the rail base and formed with a projection extending longitudinally of the rail below the base

thereof and with a tie abutting portion, and a spring bar formed at one end with a jaw for engaging one edge of the rail base and at the other end with a toggle portion adapted to be supported on said projection and in engagement with the rail base to effect a toggle grip on the rail, which toggle portion is of greater width than the distance between said projection and the rail base, whereby canting of the spring is required to permit application of said toggle portion to its operative position.

9. A rail anchor comprising a rigid member for engaging one edge of a rail base and formed with a projection extending longitudinally of the rail below the base thereof and with a tie abutting portion, and a spring bar formed at one end with a jaw for engaging one edge of the rail base and at the other end with a toggle portion adapted to be supported on said projection and in engagement with the rail base to effect a toggle grip on the rail; said toggle portion being relatively stiff and of greater width than the distance between said projection and the rail base, whereby canting of the spring is required to permit application of said toggle portion to its operative position, and a portion of the spring being relatively flexible to facilitate said canting.

10. A rail anchor comprising a rigid member for engaging one edge of the rail base and formed with a projection extending longitudinally of the rail below the base thereof and with a tie abutting portion, and a spring bar formed at one end with a jaw for engaging one edge of the rail base and at the other end with a toggle portion adapted to be supported on said projection and in engagement with the rail base to effect a toggle grip on the rail; said toggle portion being relatively stiff and of greater width than the distance between said projection and the rail base, whereby twisting of the spring is required to permit the application of said toggle portion to its operative position, and a portion of the spring being relatively flexible to facilitate this twisting of the spring.

11. A rail anchor comprising a shoe for engaging one edge of a rail and a toggle formed at one end with a portion cooperating with said shoe to effect a toggle grip on the rail and formed at the other end with a jaw for engaging the other edge of the rail with spring pressure.

12. A rail anchor comprising a shoe for engaging one edge of the rail and formed with a projection, and a spring toggle formed at one end with a portion adapted to be supported in an angular position on said projection to effect a toggle grip on the rail and formed at the other end with a jaw for engaging the other edge of the rail with spring pressure.

13. A rail anchor comprising a shoe for engaging one edge of the rail and formed with a projection, and a spring toggle formed at one end with a portion of greater width than the distance between said projection and the rail base and adapted to be supported in an angular position on said projection to effect a toggle grip on the rail and formed at the other end with a jaw for engaging the other edge of the rail with spring pressure.

14. A rail anchor comprising a shoe for engaging one edge of the rail and formed with a projection, and a spring toggle formed at one end with a portion of greater width than the distance between said projection and the rail base and adapted to be supported in an angular position on said projection to effect a toggle grip on the rail and formed at the other end with a jaw for engaging the other edge of the rail with spring pressure; the portion of said toggle engaging said projection being inclined downwardly and outwardly to provide an interlocking engagement with said shoe member.

15. A rail anchor comprising a tie abutting member formed to engage one edge of a rail and provided with a projection extending longitudinally of the rail and a spring bar formed at one end with greater width than the distance between the projection and the rail, adapted to be supported in position on said projection to effect a toggle grip on the rail during the presence of creeping pressure, and provided at the other end with a jaw for engaging the other edge of the rail base; the portion of the spring bar between the rail engaging portions thereof being of greater flexibility than the ends and adapted to be subjected to a torsional strain to permit the application of said toggle gripping portion to its operative position.

16. A rail anchor comprising a tie abutting member formed to engage one edge of the rail and provided with a projection extending longitudinally of the rail, and a spring bar formed at one end with an enlargement of greater width than the distance between said projection and the rail adapted to be supported in position on said projection to effect a toggle grip on the rail during the presence of a creeping pressure, and provided at the other end with a jaw for engaging the other edge of the rail base; the portion of the spring bar between said enlargement and said jaw being of greater flexibility than the ends and adapted to be subjected to a torsional strain to permit the application of the said enlargement to its operative position.

17. A rail anchor comprising a tie abutting member formed to engage one edge of the rail and provided with a projection ex-

tending longitudinally of the rail, and a spring bar formed at one end with an enlargement of greater width than the distance between the projection and said rail, adapted to be supported in position on said projection to effect a toggle grip on the rail during the presence of creeping pressure, and provided at the other end with a jaw for engaging the other edge of the rail base; the portion of the spring bar between said enlargement and said jaw being reduced in width to provide greater flexibility than the ends and adapted to be subjected to a torsional strain to permit the application of said enlargement to an operative position.

18. A rail anchor comprising a tie abutting member formed to engage one edge of the rail and provided with a projection extending longitudinally of the rail, and a spring bar formed at one end with an enlargement of greater width than the distance between the projection and said rail, adapted to be supported in position on said projection to effect a toggle grip on the rail during the presence of creeping pressure, and provided at the other end with a jaw for engaging the other edge of the rail base; the portion of the spring bar between said enlargement and said jaw being reduced in width to provide greater flexibility than the ends and adapted to be subjected to a torsional strain to permit the application of said enlargement to an operative position, and the upper edge of said enlargement being tapered upwardly and outwardly so as to prevent movement of the bar transversely of the rail.

19. A rail anchor comprising a tie abutting member formed to engage one edge of the rail and provided with a projection extending longitudinally of the rail, and a spring bar formed at one end with an enlargement of greater width than the distance between the projection and the rail, adapted to be supported in position on said projection to effect a toggle grip on the rail during the presence of a creeping pressure, and provided at the other end with a jaw for engaging the other edge of the rail base; the portion of the spring bar between said enlargement and said jaw being reduced in width to provide greater flexibility than the ends and adapted to be subjected to a torsional strain to permit the application of said enlargement to its operative position, and the upper and lower edges of said enlargement diverging from each other to provide said spring with an interlocking engagement with the projection on said shoe and with the adjacent edge of the rail.

20. A rail anchor comprising a shoe member for engaging one edge of a rail and formed with a projection and a toggle formed at one end with an enlarged portion adapted to assume a position between said

projection and the under edge of the rail base; the upper edge of said enlargement being formed to provide a horizontal rail gripping edge and with a lower edge extending downwardly and outwardly to effect an interlocking engagement between the spring bar and said shoe.

21. A rail anchor comprising a rigid member formed with a jaw portion for engaging one edge of a rail base and a spring bar formed at one end with a jaw for engaging the other edge of said base and with a toggle portion adapted to be positioned between a portion on the rigid member and the under surface of said rail base; said body portion of the spring intervening between its jaw and said toggle portion, being adapted to be torsioned during the application of the spring to its operative position to effect a spring grip of its jaw on the rail and to exert spring pressure between the lower edge of the rail base and said rigid member.

22. A rail anchor comprising a shoe member formed with two vertically disposed flanges connected by an arm extending longitudinally of the rail below the base and a spring bar adapted to extend through the space between the lower edge of the rail base and said arm; the end of said spring being of greater width than the distance between said arm and the lower edge of said base, whereby it is required to twist said spring to permit the end thereof to pass through the opening in said shoe.

23. A rail anchor comprising a shoe member adapted to engage one edge of a rail base and formed with an arm extending longitudinally of the rail below the base, and a spring yoke member formed with means for engaging one edge of the rail base and with a portion supported by said arm between said arm and rail base, which portion of the yoke is canted to permit it to be positioned upon said arm.

24. A rail anchor comprising a shoe member adapted to engage one edge of a rail base and formed with an arm extending longitudinally of the rail below the base, and a spring yoke member formed with a jaw portion for engaging the opposite edge of the rail base and with a portion supported by said arm between said arm and rail base, which portion of the yoke is canted to permit it to be positioned upon said arm.

25. A rail anchor comprising a shoe member and a spring member which together embrace the base of a rail and have an interlocking engagement with each other; said shoe member being formed with a jaw for engaging one edge of the rail base and with an arm extending longitudinally of the rail below said base adapted to support one end of said spring member between said arm and the bottom surface of said rail; said

spring member being provided at one end with a jaw for engaging one edge of the rail base and at the other end with a portion which normally extends below the upper surface of said arm and being adapted to be canted to effect a gripping engagement of said jaw on the rail base and to permit the positioning of said portion upon said supporting arm.

26. A rail anchor comprising two rail gripping elements one of which has a portion interposed in a diagonal position between the rail base and the other element so that it is cramped therebetween to increase the grip of the device on the rail by the creeping movement of the rail.

27. A rail anchor comprising two rail gripping elements one of which has a portion interposed in a diagonal position between the under surface of the rail base and the other element so that it is cramped therebetween to increase the grip of the device on the rail by the creeping movement of the rail.

28. In a rail anchor, the combination of a shoe to engage one edge of a rail, and a torsion yoke, one end of which is formed with a jaw to engage one edge of the rail base and the other end of which is interposed between said shoe and rail base to bear against them with spring pressure, whereby creeping movement of the rail decreases the torsion of said yoke and increases its grip on the rail.

29. In a rail anchor, the combination of a shoe to engage the edge of a rail, and a torsion yoke, one end of which is formed with a jaw to engage one edge of the rail base and the other end of which is interposed in a diagonal position between said shoe and rail base, to bear against them with spring pressure whereby creeping movement of the rail decreases the torsion of said yoke and increases its grip on the rail base.

30. In a rail anchor, the combination of a shoe to engage one edge of a rail base and a torsion spring yoke between the rail and shoe in a diagonal position so as to be moved toward a vertical position during the presence of creeping movement of the rail and the other end of which is formed with a jaw to engage the other edge of the rail base.

31. In a rail anchor, the combination of a shoe and a yoke one end of which is interposed diagonally between the shoe and the base of a rail so that it is given a cramping movement between the rail and shoe by the creeping movement of the rail and the other end of which is formed with a jaw to engage the other edge of said base.

32. In a rail anchor, the combination of a shoe and a torsion spring yoke having an enlargement with diagonal edges positioned to exert spring pressure between the rail

base and said shoe, whereby said shoe and yoke are engaged in gripping relation on the rail.

33. In a rail anchor, the combination of 5 a shoe for engaging one edge of a rail base and a spring yoke formed at one end with a jaw for engaging the other edge of said base and at the other end with means for engaging said shoe; said yoke being narrower at a point intermediate its end portions than at its ends.

34. A rail anchor comprising a shoe for engaging one edge of a rail base and a spring yoke for engaging the other edge of said base and adapted to be torsioned to 15 effect an interlocking engagement with said shoe; said yoke being provided at a point intermediate its ends with a portion of greater torsional resiliency than its end portions.
